UNITED STATES PATENT OFFICE.

CHARLES W. HEATH, OF CINCINNATI, OHIO.

AUTOMATIC GAS-ANALYSIS APPARATUS.

1,121,244.

Specification of Letters Patent. Patented Dec. 15, 1914.

Application filed February 21, 1913. Serial No. 749,811.

To all whom it may concern:

Be it known that I, CHARLES W. HEATH, a citizen of the United States, residing in Cincinnati, in the county of Hamilton and 5 State of Ohio, have invented certain new and useful Improvements in Automatic Gas-Analysis Apparatus, of which the following is a specification.

My invention relates to an improved apparatus for automatic and successive analyses of gases and the automatic and complete recording of the results of such analyses upon a moving chart preferably provided with a graduated scale.

15 The object of my invention is to record at frequent intervals in a simple, accurate and efficient manner the percentage of carbon dioxide (CO_2) in the gases leaving a furnace (such as a boiler furnace), the record thus 20 made affording a reliable indication as to the efficiency with which the fuels are being burned, it being understood that the percentage of CO_2 in the gases leaving a furnace forms a reliable index as to the efficiency 25 of the furnace. While my invention is especially adapted and intended for this purpose I do not limit it to this use alone as it may also be used to automatically record the percentage of gases other than CO_2 contained 30 in samples which may be taken from any place where it is desirable to know something of the constituents of the mixture of gases occupying a space.

35 My invention consists in the novel constructions, combinations and arrangements as herein illustrated, described and claimed.

In the drawings which serve to illustrate the construction, application and use of my invention:—the drawing shows diagrammatic view partly in vertical section and partly in elevation showing the general construction and arrangement of the apparatus.

40 In the embodiment of my invention as illustrated and which shows a preferred 45 construction, 1 represents a gas measuring chamber, having a quantity of non-absorbent liquid 2 therein and provided with a flexible bottom or diaphragm 3 which is adapted to be engaged and moved by driving liquid 4. An inlet pipe 5 communicating 50 with gas supply pipe 6 extends downwardly into said gas measuring chamber 1 and its lower end terminates at a point above the non-absorbent liquid 2 when in 55 the position shown in Fig. 1. A gas measur-

ing pipe 7 is connected to said gas measuring chamber 1 and its lower end preferably terminates a short distance above the lower end of gas inlet pipe 5. Mounted on gas measuring pipe 7 is a non-hydraulic 60 check valve 8 provided with a check 9 therein which is adapted to normally rest upon the valve seat 10 and close the upper end of said pipe 7. This pipe 7 and valve 8 serve to permit excessive amounts of gas drawn 65 into measuring chamber 1 to escape into the atmosphere without allowing any of the atmosphere to enter pipe 7 and measuring chamber 1.

I provide a non-hydraulic check valve for 70 the reason that it does not require re-adjusting or replenishing to compensate for evaporation which occurs with a hydraulic check valve. Another advantage of my non-hydraulic check valve is its uniformity of action 75 whereas a hydraulic check valve, when the height of the liquid changes (as it does in actual practice), requires either more or less pressure to overcome the static head of the liquid sealing the mouth of the gas 80 measuring pipe 7 extending below the surface of the liquid. While equal volumes of gas may be pumped, yet a slight difference in pressure due to the differences in head of the liquid through which the surplus gas is 85 discharged will make a difference in the actual amounts of gas measured off and thereby destroy the accuracy of the analyses. A 90 check valve which does not depend on a liquid and made of glass or metal, for instance, will always require the same pressure 95 to overcome its weight and the amounts of gas passed into the absorbent vessel will always be of the same volume and the same pressure each time an analysis is made.

While it might seem that a hydraulic check valve, or liquid seal, would be an advantage in preventing the leakage of atmosphere into the measuring chamber, still this is not necessary and even though a metallic 100 or glass check valve should leak slightly the atmosphere would have to completely fill the measuring pipe 7 before it could mingle with the gas to be analyzed in chamber 1. As the apparatus as herein illustrated is intended for speed as well as accuracy and simplicity the check valve might even be leaking considerably and yet before the atmosphere could have sufficient time to fill pipe 7 the liquid 2 would have reached 105 110

its lowest point in the measuring chamber 1 and would have started to rise, thereby forcing any surplus gas contained in measuring chamber 1 out through pipes 5 and 7 and valve 8 before any of the atmosphere 5 could have had time to reach the measuring chamber 1 and mingle with the gas to be analyzed.

A gas discharge pipe or tube 11 extends 10 from gas measuring chamber 1 into an absorbent vessel 12 and terminates near the bottom thereof. Vessel 12 contains an absorbing liquid 13, such as caustic potash solution. The absorbent vessel 12 is also prefer- 15 ably provided with an enlarged neck 14 which is adapted to receive filtering material 15 composed of iron wire or glass beads, for instance, which in the construction shown, surround the gas discharge pipe 11. A vertical 20 tube 16 extends upwardly in said vessel 12 from the bottom thereof to said filtering material 15 and surrounds the lower portion of gas discharge pipe 11, the lower end of 25 said tube being beveled as shown or otherwise cut away to permit the absorbing liquid to freely enter the bottom of said tube. The upper end of tube 16, preferably extends slightly above the surface of absorbing liquid 13.

A tube 17 extends from neck 14 to a second measuring device 18 which is provided with a closed receptacle 19 containing a preferably non-evaporative liquid 20 which also enters the lower end of tube 21 which ex- 30 tends downwardly into receptacle 19 to near the bottom thereof and the upper end of said tube is connected to an enlarged measuring chamber 22 having an upwardly extending neck 23 which is provided with graduations thereon by which to determine the amount of gas which has been absorbed in the absorbent vessel 12. In other words the parts 19, 20, 21, 22 and 23 constitute a second measuring device 18 for measuring the residue of gas which has not been absorbed by 35 the absorbing liquid 13. The automatic recording of these measurements may be accomplished by suitable means, such, for instance, as the means described below. A float 24 is suspended within said chamber 22 and neck 23 and is secured to a flexible connection 25 attached to a curved bar 26 upon one end of the lever-arm 27 mounted on pivot or fulcrum 28. This float 24 is adapted 40 to rise and fall with the surface of the liquid which is intermittently forced up into chamber 22 and neck 23.

The lever-arm 27 is provided with a marker 29 which engages a slowly revolving chart 30 which may be actuated by suitable means, such as clock work 31. A suitable weight or counterbalance 32 is mounted upon the lever arm 27 between its pivot or fulcrum 28 and the marker 29 to pull down 45 the end of the lever-arm 27 when the weight

of the float 24 is removed from the opposite end of said lever-arm so that the movement of said lever-arm is automatic and certain. This marking device records upon the moving chart the height to which the liquid rises in neck 23 of the second measuring device 18 and provides a permanent record of the different analyses, which records may be preserved thus affording reliable information as to the percentage of each original sample of gas which was absorbed in passing through the absorbing medium 13, and consequently providing a record of the efficiency of the furnace to which the apparatus is connected.

A gas outlet pipe 33 is connected to the pipe 17 and extends upwardly therefrom to near the top of stand pipe 34 and communicates therewith at 35 near the lower end of said stand pipe. The stand pipe 34 is supplied with water or other driving fluid 4 from a pipe 36 and said stand pipe communicates with chamber 37 beneath the flexible diaphragm 3, by means of a fluid passage 38. Stand pipe 34 also communicates at a point still nearer its lower end with the siphon pipe 39 which is provided with an air chamber 40 near its upper end and a discharge pipe 41 extending downwardly therefrom. The flexible diaphragm separates the non-absorbent liquid 2 within the chamber 1 from coming into contact with the driving liquid 4. This is important because ordinary water unless slightly acid will absorb CO₂ and would destroy the accuracy of any gas analysis apparatus which allows it to come into contact with the gas to be analyzed.

A float 42 containing mercury 43 is loosely mounted within a float vessel 44 which is connected at its bottom by a passage 44' with the stand pipe 34 near the upper end thereof. As the water rises and falls in the stand pipe 34 it will also flow into and out of float vessel 44 which will raise and lower the float 42 and thus automatically bring the mercury 43 into contact with the ends of a normally open electric circuit 45, thus automatically and intermittently opening and closing said electric circuit 45 for the purpose of causing electrically operated arm 46 to tap lever-arm 27 of the marking device at the close of each analysis and at the time the result of said analysis is recorded on chart 30, thereby enabling carbon copies of the record to be made beneath the top chart 30 similar to the manner in which copies are made on a typewriter.

I preferably construct the apparatus so that the driving liquid may be brought into contact with both measuring chambers to cause the temperature to be alike in each. This I may accomplish by causing the driving liquid 4 to flow through pipe 36 into compartment 19 thereby bringing it into 120 contact with the bottom of chamber 1.

contact with receptacle 19 before it discharges into stand pipe 34.

Fig. 1 represents the device in position to discharge a quantity of gas, a part of which is to be measured off and discharged through the absorbent vessel 12. A continuous flow of current of gas from a furnace or other source of supply passes through the gas supply pipe 6 from which samples of gas are automatically drawn, at intervals, through gas inlet pipe 5, into measuring chamber 1. The motive power or driving liquid 4 entering the stand pipe or tube 34 from pipe 36 begins rising in tubes 34, 33 and 39. A portion of this liquid also flows from stand pipe 34 through the passage 38 and forces upwardly against the flexible diaphragm 3 which causes the non-absorbent liquid 2 to rise in measuring chamber 1, thereby forcing a quantity of the gas contained above said liquid through pipe 5. As soon as the liquid has covered the mouth of pipe 5 the path of next least resistance through which gas may escape is pipe 7 and check valve 8 until the lower end of pipe 7 is sealed. Thus is trapped in measuring chamber 1 a sample of gas of a pre-determined volume and at a pre-determined pressure, which sample of gas is now to be analyzed. As the liquid continues to rise still higher in chamber 1 and now also in pipes 5 and 7 this measured gas sample is forced through discharge pipe 11 and through the absorbent vessel 12 which contains the absorbing liquid 13. This liquid 13 absorbs the CO₂ contained in the gas sample passed through it, after which the unabsorbed gas is passed from the absorbent vessel 12, through pipe 17 and into the second measuring device 18 which measures the unabsorbed gas.

The first measuring chamber being arranged to measure a uniform and definite quantity of gas each time, and the second measuring chamber being adapted to measure the residue of each sample of gas after the CO₂ therein has been absorbed, the CO₂ contained in each sample of gas measured will be indicated by the difference in quantity of each sample measured in the first measuring chamber and the residue thereof measured in the second measuring chamber.

By the time the non-absorbent liquid 2 has filled the measuring chamber 1 and reached the discharge pipe 11 it will have risen also to a still greater height in pipes 5 and 7, and the driving liquid 4 will have risen sufficiently high in tubes 34 and 39 to have filled the air chamber 40 and will now begin to overflow through tube 41, thereby starting the siphon 39, 40 and 41 which will empty tube 34 much faster than it is being filled. As stand pipe 34 is emptied, the pressure of the driving liquid 4 on the bot-

tom of diaphragm 3 is reduced, a portion of the driving liquid 4 flows from driving chamber 37 through passage 38 into stand pipe 34 and consequently the non-absorbent liquid 2 falls in pipe 5 drawing another charge of gas from pipe 6 after it into measuring chamber 1. When the liquid in pipe 34 has fallen as low as the point at which tube or pipe 39 connects to tube 34 the non-absorbent liquid 2 will have fallen below the mouths of pipes 5 and 7 and the measuring chamber 1 will again be filled with gas drawn from pipe 6 through pipe 5. The siphon 39, 40 and 41 continues to operate until the liquid is drawn from stand pipe 34 and air enters 39 and 40 breaking the liquid seal and causing said siphon to cease to operate for the time being. This intermittent rising and falling of the driving liquid in the stand pipe 34 is the principal means whereby the gas is caused to be drawn into the measuring chamber 1, correct samples measured off, and these samples then forced through other parts of the apparatus, where the analyses are made, the results of the analyses recorded on a moving chart, and the residue, or unabsorbed gas, discharged at the proper time into the atmosphere.

As the gas is discharged from the lower end of pipe 11 into the absorbing liquid, (such as caustic potash solution), it forms into a series of small bubbles which pass upwardly between the pipe 11 and the vertical tube 16 which surrounds said pipe 11. The discharge pipe 11 is placed within vertical tube 16 for the purpose of forming a narrow space therebetween which will cause the gas bubbles, as they rise to the surface of the absorbing liquid 13, to be rolled and buffeted between the surfaces of pipe 11 and tube 16, thereby bringing every particle of the gas contained in each bubble into direct contact with the absorbing liquid, so as to expose all of the gas to the absorbing liquid and insure a rapid and complete absorption of all carbon dioxid (CO₂) contained in each sample passed into the absorbing liquid. These bubbles rise to the top of tube 16 (which preferably is extended slightly above the surface of the absorbing liquid 13), where they burst, sending a spray of the liquid 13, into the filtering material 15 located above tube 16. The unabsorbed gas, before leaving vessel 12, must pass through this filtering material 15 which is wetted with the spray of the absorbing liquid. This material 15 serves the double purpose of preventing any of the absorbing liquid spray from leaving the vessel 12, and also, if by any chance a small portion of the CO₂ was not absorbed in passing up through the solution between pipe 11 and tube 16, it would certainly be absorbed in passing through this filtering material, which, as

before stated, is saturated with the absorbing liquid. As the unabsorbed portion of the gas sample now leaves vessel 12, it passes upwardly through tube 17, into closed receptacle 19 and displaces a portion of the non-evaporative liquid 20 therein by forcing it upwardly through tube 21 into measuring chamber 22 and graduated neck 23 thereby also moving the float 24 upwardly, the movement of which causes the marker 29 to automatically record upon the slowly moving chart 30 the results of the analyses.

When the fluid in tube 34 has reached a predetermined height it raises the float 42 containing mercury 43 and brings said mercury 43 into contact with both ends of a normally open electric circuit, thereby completing the circuit. Leading from this main circuit is another circuit to which is connected the magnet 47 which actuates arm 46, and this arm in turn acts on lever-arm 27, causing this arm to bear heavily on the recording surface of the chart 30 so that carbon copies of the record may be made if desired.

The float 42 and mercury 43 are parts of the main switch which automatically switches electric current on and off at the proper time to energize the magnet 54.

When the liquid is siphoned from the stand pipe 34, it will flow out of tube 33 into pipe 34 also. This unseals tube 33 and allows the residue, or unabsorbed gas, to escape from the receptacle 19 through tube 33 into pipe 34, from where it passes to the atmosphere. The tube 33 is again closed, by the rising of driving liquid 4, at the beginning of the next analysis thereby preventing the escape of gas from receptacle 19 until the proper time arrives.

My device for disposing of the residue or unabsorbed gases, is a decided improvement over other types owing to the fact that escape pipe 33 is not immersed in or surrounded by a liquid. This construction enables me to use the minimum amount of driving liquid for each analysis, greatly simplifies the construction and decreases the size or bulk of the apparatus by allowing me to dispense with a vessel containing some of the driving liquid, for escape pipe 33 to dip into. Instead, the residue of the analysis escapes through the gas pump without being able to enter the chamber or cylinder 1 of the pump, and without requiring any separate vessel, or any other liquid besides that which flows up, inside escape pipe 33, to enable the apparatus to perform its functions properly.

My invention is capable of considerable modification without departure from the scope or spirit thereof, as for instance, while I prefer to use mercury 43 in the float 42 to open and close the electric circuit 45, I do

not wish to limit myself thereto, but may substitute in place of said mercury any suitable means, such as a metal contact, for the same purpose.

I claim:

1. An automatic apparatus for gas analysis comprising a plurality of measuring chambers, a gas supply for the first of said measuring chambers, an absorbing medium, a passage for gas from said first measuring chamber into contact with said absorbing medium and into a second measuring chamber, means for automatically discharging the residue of gas from said second measuring chamber, means to show the result of the analysis, a displacing liquid which cannot absorb the gas to be analyzed for said first measuring chamber, a flexible diaphragm adapted to retain said displacing liquid between said diaphragm and the gas to be analyzed and means for moving said diaphragm to cause said liquid to rise and fall in said first measuring chamber whereby the gas is drawn into and discharged from said first measuring chamber. 91

2. An automatic apparatus for gas analysis comprising a plurality of measuring chambers, a gas supply for the first of said measuring chambers, an absorbing medium, a passage for gas from said first measuring chamber into contact with said absorbing medium and into a second measuring chamber, means for automatically discharging the residue of gas from said second measuring chamber, an upper displacing liquid, which cannot absorb the gas to be analyzed, in said first measuring chamber, and a driving liquid adjacent to the lower part of said first measuring chamber but distinct from said displacing liquid, and means whereby said driving liquid acts to cause the displacing liquid to rise and fall in said first measuring chamber, whereby the gas is drawn into and discharged from said first measuring chamber. 110

3. In an automatic apparatus for gas analysis, measuring chambers, a discharge pipe leading from the first of said chambers, means for supplying charges of gas to be analyzed to said first chamber, non-absorbing liquid adapted to rise and fall in said first chamber, a flexible diaphragm adapted to retain said non-absorbing liquid between said diaphragm and the gas to be analyzed, and a driving fluid adapted to engage and move said flexible diaphragm, means for absorbing part of the constituents in the gas and means for registering and recording the result of the analysis. 115

4. In an automatic apparatus for gas analysis, measuring chambers, an absorbent vessel through which the gas to be analyzed is forced from one measuring chamber to another, a registering device to show the result of the analysis, non-absorbing and displac- 130

ing liquids in said measuring chambers, a flexible diaphragm adapted to retain the displacing liquid in one of said measuring chambers, and means for moving said diaphragm to cause said displacing liquid to measure and discharge a quantity of gas and then recede to allow another sample to be collected for analysis, and so on indefinitely.
